CLAIM

The ornamental design for a pet water dispenser, as shown and described.

DESCRIPTION

FIG. 1 is a top perspective view of a pet water dispenser showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

Broken lines and unshaded portions contained within broken lines depict unclaimed features of the pet water dispenser that form no part of the design claim but are shown for illustrative purposes.

1 Claim, 8 Drawing Sheets
